(57) **CLAIM**

We claim the ornamental design for a socket wrench with handle-housed drive sockets, as shown and described.

DESCRIPTION

FIG. 1 is a perspective view of a socket wrench with handle-housed drive sockets;

FIG. 2 is a top plan view of the socket wrench with handle-housed drive sockets of FIG. 1;

FIG. 3 is a bottom plan view of the socket wrench with handle-housed drive sockets of FIG. 1;

FIG. 4 is a left side elevational view of the socket wrench with handle-housed drive sockets of FIG. 1, the broken lines of the socket wrench are for illustrative purposes only and form no part of the claimed design;

FIG. 5 is a right side elevational view of the socket wrench with handle-housed drive sockets of FIG. 1;

FIG. 6 is a front elevational view of the socket wrench with handle-housed drive sockets of FIG. 1; and,

FIG. 7 is a rear elevational view of the socket wrench with handle-housed drive sockets of FIG. 1.
